UNITED STATES PATENT OFFICE.

HENRY F. BELCHIER, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,331, dated July 13, 1897.

Application filed June 15, 1897. Serial No. 640,946. Term of patent 14 years.

To all whom it may concern:

Be it known that I, HENRY F. BELCHIER, a citizen of the United States, residing at Chicago, in the county of Cook, State of Illinois, 5 have invented and produced a certain new and useful Design for Prism-Lights, of which the following is a description.

My invention relates to a new design for prism-lights, and is illustrated in the accompanying drawings, wherein—

Figure 1 is a perspective view of a prism-light embodying my design. Fig. 2 is a sectional view of Fig. 1.

As illustrated in the drawings, the prism-light A is provided with a series of prisms B B, extending across its face, and is also pro-

vided with the straight edge C and the two curved edges D D.

Certain angles and dimensions of the prism-lights and the prisms are shown; but the essential features of my design are found in a prism-light provided with a series of projecting prisms extending across its face and having three edges, two of which consist of convex curves, the third being straight, as shown. 20 25

I claim—

The design for a prism-light as herein shown and described.

HENRY F. BELCHIER.
